(57) **CLAIM**

The ornamental design for a lighting module visor, as shown and described.

DESCRIPTION

FIG. 1 is a perspective view of an embodiment of the claimed design;

FIG. 2 is a top plan view of FIG. 1;

FIG. 3 is a bottom plan view of FIG. 1;

FIG. 4 is a front elevation view of FIG. 1;

FIG. 5 is a back elevation view of FIG. 1;

FIG. 6 is a right side elevation view of FIG. 1;

FIG. 7 is a left side elevation view of FIG. 1;

FIG. 8 is a perspective view of the embodiment of FIGS. 1-7 in a typical environment in which it is used;

FIG. 9 is a perspective view of another embodiment of the claimed design. The only difference is the showing of indeterminate side length (the length of the side can vary but with the same ornamentation as the part in solid lines); and,

FIG. 10 is a perspective view of another embodiment of the claimed design. The only difference is showing of indeterminate top length (the length of the portion can vary but with the same ornamentation as in solid lines).

The broken lines showing a lighting module in FIG. 8 illustrates environmental structure and forms no part of the claimed design. The broken lines used to indicate the design having no specific length in FIGS. 9 and 10 form no part of the claimed design.
